UNITED STATES PATENT OFFICE.

DAVID GAY AND JOHN H. PURKISS, OF LONG BAR, CALIFORNIA.

IMPROVED QUARTZ-CRUSHER.

Specification forming part of Letters Patent No. 43,304, dated June 28, 1864.

To all whom it may concern:

Be it known that we, DAVID GAY and JOHN H. PURKISS, of Long Bar, in the county of Yuba and State of California, have invented a new and useful Improvement in Hydraulic Quartz Crushers; and we do hereby declare that the following is a full, clear, and exact description of the same, reference being had to the accompanying drawings, making a part of this specification, in which—

Figure 1 is a side elevation; Fig. 2, a plan. This invention consists in the attachment of a water-wheel to the side of the ordinary crushing-wheel of a "Chillian mill," so that the said water-wheel will travel around in the same path as the crushing-wheel, and will furnish motive power for driving the mill. Each crushing-wheel may, if desired, have two water-wheels attached to it, one upon each side of the crushing-wheel, as indicated in red outline, Fig. 2.

Quartz-mills made according to our improvement may have one, two, or more crushing-wheels and attached water-wheels, according to the supply of water or the requirements of the builder.

The foundation A, annular basin B, in which the crushing-wheels move, and the central pivot, C, around which the crushing-wheels D travel, are, together with the wheels D, constructed in the ordinary manner, well understood by practical mill-wrights. Upon the inner side of each crushing-wheel D we attach an overshot water-wheel, E, which is constructed according to any of the well-known methods. As shown in the drawings, the buckets F are attached to an inner drum, G, the buckets and drum being arranged between two flanges, H H. A horizontal shaft, I, passes through the crushing-wheels D, and also through the water-wheels E. This shaft has an eye or aperture at its center, where it receives the central pivot, C, as shown in Fig. 1. Each crushing-wheel and its attached water-wheel turns loose upon shaft I. Between the two water-wheels and rising from the shaft C are two standards, K K, upon the upper extremities of which is mounted a water-trough, L, which extends across over both water-wheels. There is an aperture, M M', at each end of this trough L, but on opposite sides. When a running stream or supply of water is allowed to flow into the trough L, the water

issues through the apertures M M' upon the buckets of the water-wheels, as shown by the arrows, and sets them in motion, thus causing the crushing-wheels also to move and travel around in the basin B and crush the quartz contained therein. Thus the crushing-wheels, water-wheels, and supply-trough, together with the horizontal shaft I, all move together. As the wheels revolve the water brought down in the buckets is discharged upon the aprons N, one of which is placed in front and at the lower part of each wheel E, the aprons N being supported by arms O O, which are saddled across the central shaft, I, in the manner shown in Fig. 1, a filling-block or bar, S, being placed between shaft I and the bars O, as shown in Fig. 1. The aprons N receive and conduct the waste water away from the wheels into the sewer pipes P, and thus prevent it from flowing into the basin B. To assist in conducting the water toward the pipes P, the central part of the foundation Q is made concave, as shown. The outer edge of the basin B is provided with a perforated screen, R, to prevent the undue escape of the quartz. The mill is also to be furnished at other points with the channels, sluices, screens, and pockets necessary or convenient for such machines, to assist in saving or preventing the waste of the substance to be crushed.

This mill may be used for crushing all kinds of ores and other substances.

We do not confine ourselves to any particular details in the construction of our mills, because these may be varied according to the ordinary skill or desire of the mechanic or owner.

Having thus described our invention, what we claim as new, and desire to secure by Letters Patent, is—

1. The attachment of the water-wheel to the side of the crushing-wheel, substantially in the manner herein shown and described, so that the water-wheel will drive and travel with the crushing-wheel, all as set forth.

2. The combination; with the water-wheels, of the water-conducting aprons, substantially as herein shown and described.

DAVID GAY.
JOHN H. PURKISS.
